CLAIM

What is claimed is the ornamental design for a brewer, as shown and described.

DESCRIPTION

FIG. 1 is a front right side perspective view of the brewer;

FIG. 2 is a rear right side perspective view thereof;

FIG. 3 is a rear left side perspective view thereof;

FIG. 4 is a front left side perspective view thereof;

FIG. 5 is a front elevational view thereof;

FIG. 6 is a right side elevational view thereof;

FIG. 7 is a rear elevational view thereof;

FIG. 8 is a left side elevational view thereof;

FIG. 9 is a top view thereof; and,

FIG. 10 is a bottom view thereof.

The broken lines shown in the drawings are for purposes of illustrating portions of the brewer and form no part of the claimed design.
